By John J. Jochum Jr. Atty.

UNITED STATES PATENT OFFICE.

HENRY T. SCHIFF, OF CHICAGO, ILLINOIS, ASSIGNOR TO VITANOLA TALKING MACHINE COMPANY, OF CHICAGO, ILLINOIS, A CORPORATION OF ILLINOIS.

DESIGN FOR A SOUND-REPRODUCING CABINET.

56,569.

Specification for Design.

Patented Nov. 9, 1920.

Application filed March 22, 1920. Serial No. 367,872. Term of patent 3½ years.

To all whom it may concern:

Be it known that I, HENRY T. SCHIFF, a citizen of the United States, residing at Chicago, in the county of Cook and State of Illinois, have invented a new, original, and ornamental Design for a Sound-Reproducing Cabinet, of which the following is a specification, reference being had to the accompanying drawing, forming part thereof.

The figure is a view of a sound reproducing cabinet, showing my new design.

I claim:

The ornamental design for a sound reproducing cabinet, as shown.

HENRY T. SCHIFF.
